JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

VERTICAL COKING-RETORT OVEN

Application filed November 18, 1925. Serial No. 69,928.

This invention relates to improvements in vertical retort apparatus, more particularly for distilling or coking carbonaceous materials.

5 The chief object of the present invention is to provide a system of heating in vertical retort apparatus which will permit of substantial segregation in different regions of the apparatus, of portions of the system between 10 which a draft differential exists.

The invention consists broadly in providing a channel extending transversely to a number of heating walls greater than two and having duct connection with each of said 15 heating walls.

In the preferred embodiment of the invention a transverse channel extends transversely to at least four heating walls and receives the waste gases exhausted from heating walls connected to on-regenerators and directs said waste gases into heating walls connected to off-regenerators, the transverse channel being thus always traversed by waste 20 gases.

25 A single transverse channel connected to all the heating walls of a battery may be used, or in large batteries more than one such channel, each connected to at least four heating walls, may be employed.

30 In the accompanying drawings forming a part of this specification and showing, for purposes of exemplification only the preferred form and manner in which the invention may be practiced:

35 Figure 1 is a vertical sectional elevation taken longitudinally of a retort in a plane indicated by the line E—E of Fig. 3, of an apparatus in accordance with said form;

40 Fig. 2 is a horizontal section taken in the horizontal plane indicated by the line K—K in Fig. 1;

45 Fig. 3 is a composite horizontal section taken in the different horizontal planes indicated by the lines A—A, B—B, C—C and D—D of Fig. 1;

50 Fig. 4 is a vertical section taken longitudinally through a vertical flue in a plane indicated by the line G—G of Fig. 3;

55 Fig. 5 is a vertical section taken trans-

versely through the regenerators in a plane indicated by the line L—L of Fig. 3.

The same characters of reference designate the same parts in each of the several views of the drawings.

In its present embodiment, the invention is incorporated in a vertical retort battery of the special construction described in my co-pending application, filed January 24, 1924, Serial No. 684,342, for producing metallurgical coke and designed for the employment of the combination oven principle involving the alternative use of an extraneously derived relatively lean gas, or with a relatively rich gas for fuel. The invention however 60 is capable of other valuable applications, for example, to apparatus generally useful in the heat treatment of materials, or to constructions providing for heating solely with relatively lean gas according to the "gas oven" 65 principle, or to construction providing for the heating solely with relatively rich gas according to the "coke oven" principle.

Referring to the drawings, there are shown 70 views of a vertical retort battery of the by-product type, as hereinbefore mentioned. The vertical retort battery comprises in its construction a series of distilling chambers, such as the series 11 of vertically elongated 75 retorts or coking chambers, the retorts of the series being contiguous to intermediate heating walls 12. The heating walls 12 form the side walls of the respective retort chambers 11, both being preferably substantially rectangular in horizontal section and elongated 80 transversely of the battery structure but relatively narrow longitudinally of said battery, as shown in Fig. 3. The heating walls and the retort chambers extend to a great 85 height as compared with their horizontal dimensions, and the retorts 11 are tapered toward the top, to facilitate passage of the material being treated from top to bottom of the retort. According to the present embodiment of the invention, the series of retorts and corresponding intermediate heating walls are respectively arranged and extend 90 along one side of the battery assembly, as shown in Fig. 3, whereas the regenerators extend along the other side of the battery as 95 100

sembly. The outer ends of the respective retorts as well as the heating walls are closed by the side refractory wall structure, indicated at 15 and the inner ends of said heating walls and coking chambers are separated from the series of regenerators by the interior refractory wall structure 16, as shown in Figs. 1, 2 and 3. The outer ends of the regenerators are closed by the side refractory wall structure 17.

10 The coal to be coked is charged into the upper ends of the retorts 11 and the completed coke is discharged through openings at the bottom of said retorts. Because of the great height of the retorts as compared with their horizontal dimensions, the retort battery is preferably employed as a continuous vertical retort, with consequent great capacity for coke and by-product production. 15 When so employed, a continuous feed of carbonaceous material may be maintained through the retorts 11, with continuous discharge of the finished coke from the bottoms of such retorts.

20 The heat for coking the charges of coal in the several retorts 11 is derived from the heating walls 12 corresponding to said retorts. Each heating wall 12 is constituted of a plurality of upper flue sections 37 and a 25 plurality of lower flue sections 38, the former being connected with the latter in such a manner as to form continuous vertical flue passages extending from top to bottom of the heating walls. As shown in Fig. 1, the flue sections 37 and 38 are of substantially equal length, the flue sections 38 extending upwardly to a horizontal plane substantially midway the top and bottom of the heating wall, and the upper flue sections 37 extend from said 30 lower flue sections 38 to the top 39 of the battery structure. The flues of both upper and lower sections 37 and 38 of a heating wall are operatively disposed in a single group, that is to say, all of said flue sections operate 35 concurrently for flow in the same direction; however, according to the invention, the flues of half the number of adjacent heating walls, for example the group K (see Fig. 3) operate for downflow combustion, or as downflow 40 flame flues, while the flues of the other half of the number of heating walls, for example the group L, operate for upflow of waste gases or as exhaust flues. After reversal the 45 flues of the heating wall group L become downflow flame flues and the flues of the heating wall group K become upflow exhaust flues. According to this mode of operation, 50 during any reversal period some of the retort chambers M are receiving flame heat from the heating walls on both sides, the middle retort chamber N is receiving flame heat from one side only, and other retort chambers such as O are located between upflow 55 exhaust gas flues. However, as the reversals 60 take place at regular intervals all the retort

chambers are subjected during the coking period to substantially equal exposure to the heat of burning flame.

As shown in Fig. 4 each upper flue section 37 is connected by a pair of passages 40 with the lower flue section 38 to form a continuous flue channel. The passages 40 are located at the sides of the nozzle block 41 set in the flue channel at the point where the upper flue section 37 merges into the lower flue section 38 and substantially midway the top and bottom of the heating wall. At their bottoms the lower flue sections 38 of each of the heating walls are respectively connected by ports 42 with a horizontal channel 43 extending longitudinally of the heating wall. According to the present invention the horizontal channels 43 of at least four adjacent heating walls, and in the illustrated instance all of the horizontal channels 43 of the battery, are connected to a channel or passageway 144 which extends transversely through the intermediate wall structure 16, as shown in Fig. 3. By this arrangement, the bottoms of the burning lower flue sections 38 of the heating wall group K are connected with the bottoms of upflow lower flue sections 38 in the heating wall group L by means of the said passageway 144 which conveys the waste gases from the former to the latter flue sections.

As shown in Figs. 2 and 3, the regenerators 45 are located in a single series along one side of the battery, with the major vertical plane of the regenerators parallel to the major vertical planes of the retorts and heating walls. Operatively, the series of regenerators 45 is arranged into two groups R and S, each group comprising four regenerators. The regenerators of the group R are segregated at one end, and those of the group S at the other end, of the row as shown in Fig. 3. When the several regenerators of the group R are operating for inflow, that is to say, for delivering preheated gaseous media to the flues of the heating walls, the several regenerators of the other group S are operating for outflow to extract heat from the gases discharged into the regenerators from the flues. On reversal of the battery, at the end of each operating period, the inflow regenerators become outflow regenerators and the outflow regenerators become inflow regenerators.

Each regenerator 45 is preferably a high narrow upright chamber substantially rectangular in horizontal section and containing open brickwork or checkerwork and having a sole channel 47 underneath and opening up into the checkerwork. The several regenerators are heated by the hot combustion products that are exhausted from the flame or combustion flues hereinbefore mentioned and then, on reversal, impart heat to the medium that they feed to the flues. Whether of the group R or of the group S, the regenerators

are all so connected with appropriate flues, that the inflow always takes place in an upward direction through the regenerators, whereas the outflow is always downwardly through said regenerators.

In the operation of the battery, when an extraneously derived gas, such as producer gas is employed, the several regenerators of the group R, when in inflow operation, deliver air and fuel gas to the flame flues of the heating walls K during the period when the latter are operating for downflow combustion; these regenerators R receive the exhaust gases from the flame flues of the heating walls K, after reversal, that is to say, during the period when the flame flues of said walls K are operating for upflow exhaust of waste gases. On the other hand, the several regenerators of the group S operate for inflow of air and fuel gas to deliver the same to the flues of the heating walls L, when the latter are operating for downflow combustion, and the said regenerators S operate for outflow to receive the exhaust gases from the flues of said heating walls L during the period when the latter are operating for upflow exhaust of waste gases. This method of operation permits all the regenerators of the battery to be directly connected at their upper ends to the tops of the heating walls and by said connections to the tops of the upper flue sections 37 which said regenerators serve.

During producer gas operation, the several regenerators of each group R or S are constituted of two air regenerators A and two gas regenerators P, when operating for inflow, and all the regenerators of either group R or S are constituted of waste gas regenerators W when operating for outflow. However, the several regenerators R operate for inflow while at the same time the several regenerators S operate for outflow and, on reversal of the flow through the flame flues, the several regenerators S are changed to the inflow function while concurrently the other regenerators R are changed to the outflow function.

Each regenerator A whether of the group R or of the group S leads at its upper end into a duct 53, which duct 53 is directly connected with the horizontal flues 54 at the top of the heating wall 11 corresponding to said regenerator. In like manner, each regenerator P, whether of the group R or S, leads at its upper end into a duct 63 directly connected with the horizontal channel 64 at the top of the heating wall corresponding to said regenerator. Thus all the connections between the regenerators and the heating walls extend directly from the top of the former to the top of the latter. Each heating wall 11 has a pair of such horizontal channels 54 and 64 leading respectively from regenerators A and P of the group corresponding to said heating wall. The horizontal channel 54 of

each heating wall is directly connected with the tops of the several upper flue sections 37 by ports 55; and the horizontal channel 64 is likewise directly connected with the tops of said upper flue sections 37 by ports 65. By this arrangement the tops of the upper flue sections 37 of each heating wall are directly connected with a pair of regenerators A and P, when the flue sections are operating for downflow combustion, or W-W when the flue sections are operating for upflow exhaust of waste gases. As shown in Figs. 7 and 8 the ports 55 and 65 leading into the flue sections 37 of each heating wall are each provided with plugs 66 having inclined faces 67. This construction provides flaring nozzles in the ports 55 and 65 to direct the air and gas, or air during coke oven gas operation, into the center of the corresponding flue section with the required velocity. The draft through the ports 55 and 65 may be regulated by slide bricks positioned in the bottoms of the horizontal flues 54 and 64.

Means are provided for leading gaseous media, for example air and producer gas, from the tops of the inflow regenerators directly to the tops of the lower flue sections 38 of the downflow operating heating walls. By this construction, additional supplies of air and fuel gas are introduced midway the tops and bottoms of the continuous vertical flue channels and downburning flame is prolonged throughout substantially the entire extent of the flue channels. Referring particularly to Figs. 3 and 7, the horizontal channel 54 of each heating wall is connected by a series of ports 71 with a series of vertical feed channels 72 located between the flue channels. Similarly the horizontal channel 64 of each heating wall is connected by a series of ports 81 with a series of similar vertical feed channels 82. As shown in Fig. 1 the vertical feed channels 72 and 82 extend down to the bottoms of the upper flue sections 37 and the channels 72 and 82 of each adjacent pair are provided with ducts which converge into and through the nozzle block 41 at the top of the lower flue section 38. By this construction, each lower flue section 38 is provided at its top with duct connections leading from a pair of feed channels 72 and 82 and through these channels with separate horizontal flues 54 and 64 leading from separate regenerators. As shown in Fig. 1, the interior feed channels 72 and 82 are provided with a pair of diverging ducts respectively leading through the nozzle blocks 41 of adjacent flue sections, whereas the feed channels on the opposite extreme ends of the heating walls are only required to have one duct.

In operating with extraneously derived producer gas, the invention thus provides supply connections to the tops of each downburning lower flue section 38 for permitting pro-

ducer gas and air to flow from separate producer gas and air regenerators P and A and to propagate additional flame in the downburning lower flue sections. Any waste gases from the upper flue sections 37 together with the waste gases from the bottom of the lower flue sections 38, of the downburning heating walls, pass through the ports 42 into the horizontal channels 43 in the bottoms of the downburning heating walls and thence through the transverse passage 144 into the similar channels 43 in the upflow operating heating walls. From the channels 43 of the upflow operating heating walls the waste gases pass through the ports 42 and thence upwardly through the lower flue sections 38 of said walls. At the tops of the lower flue sections 38, the waste gases discharge through the side passages 40 and into the upper flue sections 37 and feed channels 72 and 82. Passing upwardly through the outer flue sections 37 and feed channels 72 and 82, the waste gases discharge at the tops of the upflow operating heating walls into the horizontal flues 54 and 64, through which the waste gases are conveyed to the waste gas regenerators. Passing downwardly through the waste gas regenerators W the waste gases heat up the checkerwork for the next inflow operating period of said regenerators. The draft through the ports 71 and 81 which connect the horizontal flues 54 and 64 with the vertical feed channels 72 and 82 may be regulated by slide bricks positioned in the bottoms of the horizontal flues 54 and 64. Inspection ducts 86 extending through the top 39 of the battery structure and positioned over the ports 55 and 65 of each heating wall afford access to the interior of the horizontal flues 54 and 64, for the purpose of variably adjusting the slide bricks.

Provision is made for operating the battery alternatively with a relatively rich gas, such as coke oven gas and for supplying said gas to the tops of both the upper sections 37 and the lower sections 38 of the continuous downburning vertical flue channels. As shown in Fig. 1, vertical coke oven gas ducts 91 lead through the top 39 of the battery structure respectively into the tops of the upper flue sections 37 of each heating wall for the purpose of supplying coke oven gas to the tops of the downburning continuous flues, during coke oven gas operation of the battery. These coke oven gas ducts 91 may be equipped with the usual nozzles (not shown) and receive a supply of coke oven gas from a coke oven gas main. Within each nozzle block 41 is a vertical coke oven gas duct 93 (Fig. 4) provided with a nozzle, not shown. The vertical ducts 93 lead directly into the tops of the lower flue sections 38 for the purpose of supplying coke oven gas to the tops of such flue sections as are operating for downflow combustion. The ducts 93 are

supplied with coke oven gas from horizontal supply channels 95, which extend lengthwise through the respective heating walls 12, as shown in Fig. 1, and intersect all of the nozzle blocks 41. The channels 95 may be supplied from a coke oven gas main running lengthwise of the battery. Suitable reversing mechanism is provided for permitting a supply of coke oven gas to the upper ducts 91 and also ducts 93 that lead into downburning flue sections, and for cutting off the supply of gas from the flues of the heating walls which operate for exhaust of waste gases. During coke oven gas operation, the inflow regenerators A and P of either series R or S may be employed for conjointly feeding air to the flues, or, if desired, one regenerator may feed air and the other diluent waste gas, in accordance with the diluent principle. The required additional air supply for maintaining combustion in the lower flue sections 38 comes from the feed channels 72 and 82. In ordinary coke oven gas operation both channels 72 and 82 feed air to the tops of the lower flue sections 38, and in diluent coke oven gas operation the channels 72 may feed air and the channels 82 diluent waste gas. The exhaust of the waste gases from the upflow operating flues is effected in exactly the same manner as in producer gas operation.

The transverse channel 144, which forms the main feature of the present invention, preferably extends the whole length of the battery and serves in common all of the heating walls. In large batteries however more than one transverse channel may be used, each serving a group of at least four heating walls.

The preferred employment of the transverse channel 144 is as described, viz., to carry waste gases from a series of segregated flame traversed heating walls into a series of segregated waste gas traversed heating walls. It is however within the scope of the invention to employ transverse channels each duct connected with three or more heating walls, in lieu of the ducts of the above mentioned application Serial No. 684,342 which connect the two opposite walls of vertical retorts by passing around the end of each alternate single retort. In such an adaptation of the invention each transverse channel 144, in one working period, would distribute air or lean gas to the several heating walls served thereby, and in the next working period would convey waste gases from the same heating walls, whereas in the illustrated embodiment of the invention the transverse channel is, or the transverse channels are, always traversed by waste gases.

Referring more particularly to the regenerator arrangement described and illustrated herein, it will be seen that not only are all the inflow regenerators and flame traversed heating walls arranged at one end of the battery and all the outflow regenerators and

waste gas traversed heating walls at the other end of the battery, with only one place of division between these two battery portions between which different internal draft suction 5 prevail, but also that in lean gas operation no fuel gas regenerator P is ever alongside a waste gas regenerator W. An air regenerator W always intervenes between the waste gas regenerators W and the fuel gas regenerator P nearest thereto.

Where a group of ovens such as shown in Fig. 2 constitutes a block or unit forming part of a battery containing more than one such block or unit, the regenerator disposition 15 and reversing mechanism of the next block or unit to the left is preferably so organized that its group of inflow regenerators is alongside the group R of Fig. 2. This arrangement gives maximum segregation of 20 chambers and passages subject to similar internal draft conditions; it also maintains in lean gas operation, the insulation of fuel gas regenerators from waste gas regenerators when the groups K and L contain an odd 25 number of heating walls and the extreme outside regenerator is a fuel gas regenerator P, as is the case in Fig. 2. When the groups K and L contain an even number of heating walls the extreme outside regenerator of the 30 group R is an air regenerator A and the insulation of the gas regenerators P is maintained irrespectively of the regenerator arrangement in a neighboring block or unit.

As a consequence of the segregation of all 35 the outflow regenerators at one end of the battery, and all the inflow regenerators at the other end of the battery, internal partitions in the regenerator spaces can be largely eliminated. Thus in Fig. 2 double width regenerators are employed in both groups R and S except at the ends of the groups, instead of 40 pairs of narrower regenerators. In a battery in which air only has to be preheated, all internal partitions in each regenerator group 45 could be eliminated, each group R and S thus becoming a single large regenerator chamber.

My invention is hereinabove set forth as embodied in one particular form of construction, but I do not limit it thereto or to less 50 than all the possible forms in which the same invention as hereinafter claimed may be embodied and distinguished from prior devices.

I claim:

1. In a vertical retort battery: a series of 55 alternate vertical retorts and flued heating walls therefor, arranged side by side; said heating walls being operatively disposed in groups of at least two heating walls each, operable for inflow combustion and outflow 60 of waste gas in alternation with each other; means for conveying heating gases extending continuously and transversely of at least four heating walls in an adjoining pair of said groups; and duct connections from the respective heating walls to the conveying

means; whereby to conduct the combustion products from the flues of a plurality of the heating walls in one of the groups to the flues of a plurality of the heating walls in another of the groups as one of the groups is 70 fired in alternation with another of the groups.

2. In a vertical retort battery: a series of alternate vertical retorts and flued heating walls therefor, arranged side by side; reversible regenerators; duct connections communicably connecting the regenerators and the flues of the heating walls; said heating walls being operatively disposed in groups, of at least two heating walls each, operable for inflow combustion and outflow of waste gas in alternation with each other; means for conveying heating gases extending continuously and transversely of at least four heating walls in an adjoining pair of said groups; and duct 80 connections from the respective heating walls to the conveying means; whereby to conduct the combustion products from the flues of a plurality of the heating walls in one of the groups to the flues of a plurality of the heating walls in another of the groups as one of the groups is fired in alternation with another of the groups.

3. In a vertical retort battery: a series of alternate vertical retorts and vertically flued 95 heating walls therefor, arranged side by side; reversible regenerators; duct connections communicably connecting the regenerators and the flues of the heating walls; said heating walls being operatively disposed in groups, of at least two heating walls each, operable for inflow combustion and outflow of waste gas in alternation with each other; means for conveying heating gases 100 extending continuously and transversely of at least four heating walls in an adjoining pair of said groups; and duct connections from the respective heating walls to the conveying means; whereby to conduct the combustion products from the flues of a plurality of the heating walls in one of the groups to the flues of a plurality of the heating walls in another of the groups as one of the groups is fired in alternation with another of the groups.

4. In a vertical retort battery: a series of alternate vertical retorts and flued heating walls therefor, arranged side by side; reversible regenerators; connections for conveying alternately in successive periods preheated combustion medium from the regenerators to 115 the flues of the heating walls and waste gases to the regenerators from the flues of the heating walls; said heating walls being operatively disposed in groups, of at least two heating walls each, operable for inflow combustion 120 and outflow of waste gas in alternation with each other; waste gas conveying means continuously extending transversely of at least four heating walls in an adjoining pair of said groups; and duct connections from the flues of 125

130

the respective heating walls to the conveying means; whereby to conduct the combustion products from the flues of a plurality of the heating walls in one of the groups to the flues of a plurality of the heating walls in another of the groups as one of the groups is fired in alternation with another of the groups.

5. In a vertical retort battery: a series of alternate vertical retorts and vertically flued heating walls therefor, arranged side by side; reversible regenerators; connections for conveying alternately in successive periods preheated combustion medium from the regenerators to the flues of the heating walls and waste gases to the regenerators from the flues of the heating walls; said heating walls being operatively disposed in groups, of at least two heating walls each, operable for inflow combustion and outflow of waste gas in alternation with each other; waste gas conveying means continuously extending transversely of at least four heating walls in an adjoining pair of said groups; and duct connections from the flues of the respective heating walls to the conveying means; whereby to conduct the combustion products from the flues of a plurality of the heating walls in one of the groups to the flues of a plurality of the heating walls in another of the groups as one of the groups is fired in alternation with another of the groups.

6. In a vertical retort battery, a plurality of vertical retorts, vertically flued heating walls flanking said retorts, reversible vertical flow regenerators, connections between the tops of the regenerators and the tops of the vertical flues in the heating walls for conveying alternately in successive periods preheated combustion medium and waste gases from the regenerators to the vertical flues and reversely, waste gas conveying means extending continuously transversely to at least four heating walls, and duct connections from the bottoms of the vertical flues of the respective heating walls to said conveying means.

7. In a vertical retort battery, a plurality of vertical retorts, fluid heating walls flanking said retorts and disposed therewith in a row extending along one side of the battery, reversible regenerators communicably connected with the flues of said heating walls and disposed in a row extending along the opposite side of the battery, and means for conveying heating gases from the flued heating walls at one side of the centre of the row to the flued heating walls at the opposite side of the centre of the row.

8. In a vertical retort battery, a plurality of vertical retorts, vertically flued heating walls flanking said retorts and disposed therewith in a row extending along one side of the battery, reversible regenerators communicably connected with the flues of said heating walls and disposed in a row extending along the opposite side of the battery, and means

for conveying heating gases from the flued heating walls at one side of the centre of the row to the flued heating walls at the opposite side of the centre of the row.

9. In a vertical retort battery, a plurality of vertical retorts, vertically flued heating walls flanking said retorts and disposed therewith in a row extending along one side of the battery, reversible regenerators disposed in a row extending along the opposite side of the battery, connections between the tops of the regenerators and the tops of the vertical flues for conveying therebetween alternately in successive periods preheated combustion medium and waste gases, waste gas conveying means continuously extending transversely to at least four heating walls, and duct connections from the bottoms of the vertical flues of the respective heating walls to said conveying means.

10. In a vertical retort battery, a plurality of vertical retorts, vertically flued heating walls flanking said retorts and disposed therewith in a row extending along one side of the battery, reversible regenerators disposed in a row extending along the opposite side of the battery, direct duct connections between the tops of the regenerators and the tops of the vertical flues in the heating walls, a channel continuously extending transversely to at least four heating walls, and duct connections from said channel to the bottoms of the several heating walls.

11. In a vertical retort battery, a plurality of vertical retorts, vertically flued heating walls flanking said retorts and disposed therewith in a row extending along one side of the battery, reversible regenerators disposed in a row extending along the opposite side of the battery, direct duct connections between the tops of the regenerators and the tops of the vertical flues in the heating walls, a channel continuously extending transversely to at least four heating walls and located between the row of regenerators and the row of retorts and heating walls, and duct connections from said channel to the bottoms of the flues in several heating walls.

12. In a vertical retort battery, an odd number of vertical retorts, flued heating walls alternating with the retorts, and disposed therewith in a row, reversible regenerators disposed in a row alongside and at substantially the same level as the row of retorts and heating walls and with the inflow and outflow regenerator portions respectively segregated on opposite sides of the center of the row, and a system of duct connections communicating with said regenerators and with said flued heating walls and so organized that the middle retort may have always an inflow heating wall on one side and an outflow heating wall on the opposite side and retorts on one side of the middle retort may have all their flued walls

fed by inflow, whilst retorts on the opposite side of the middle retort may have all their flued walls adapted to discharge into outflow regenerator portions in any period between 5 draft reversals.

13. In a vertical retort battery, an odd number of vertical retorts, flued heating walls alternating with the retorts and disposed therewith in a row, reversible regenerators disposed in a row alongside and at substantially the same level as the row of 10 retorts and flued heating walls and with the inflow and outflow regenerator portions respectively segregated on opposite sides of the center of the row, a system of duct connections communicating with said regenerators and with said flued heating walls and so organized that the middle retort may have always an inflow heating wall on one 15 side and an outflow heating wall on the opposite side and retorts on one side of the middle retort may have all their flued walls fed by inflow, whilst retorts on the opposite side of the middle retort may have all their 20 flued walls adapted to discharge into outflow regenerator portions in any period between draft reversals, and means for admitting fuel gas to some of the regenerators other than those at the junction between inflow and outflow 25 regenerator portions.

14. In a vertical retort battery, an odd number of vertical retorts, flued heating walls alternating with the retorts and disposed therewith in a row, reversible regenerators disposed in a row alongside and at substantially the same level as the row of 30 retorts and flued heating walls and with the inflow and outflow regenerator portions respectively segregated on opposite sides of the center of the row, a system of duct connections communicating with said regenerators and with said flued heating walls and so organized that the middle retort may have always an inflow flued heating wall on one 35 side and an outflow flued heating wall on the opposite side and retorts on one side of the middle retort may have all their flued walls fed by inflow, whilst retorts on the opposite side of the middle retort may have all their 40 flued walls adapted to discharge into outflow regenerator portions in any period between draft reversals, and means for admitting fuel gas to interior regenerator portions.

15. In a vertical retort battery, a plurality 45 of side-by-side vertical retorts, heating walls intermediate said retorts, vertical flues in the heating walls constituted of upper and lower flue sections, reversible regenerators, connections extending separately to both upper and lower flue sections of the heating 50 walls for conveying alternately in successive periods preheated combustion medium from the regenerators to the flues of the heating walls and waste gases to the regenerators 55 from the flues of the heating walls, waste 60

gas conveying means continuously extending transversely to at least four heating walls, and duct connections communicably connecting the respective flued heating walls to said conveying means.

16. In a vertical retort battery, a plurality of side-by-side vertical retorts, heating walls intermediate said retorts, vertical flues in the heating walls constituted of upper and lower flue sections, reversible regenerators, connections extending separately to both upper and lower flue sections of the heating walls for conveying alternately in successive 70 periods preheated combustion medium from the regenerators to the flues of the heating walls and waste gases to the regenerators from the flues of the heating walls, waste gas conveying means continuously extending transversely to at least four flued heating walls, duct connections communicably connecting the respective heating walls to said conveying means, and rich gas conduits communicating with both upper and lower flue 75 sections.

17. In a vertical retort battery, a plurality of side-by-side vertical retorts, heating walls intermediate said retorts, vertical flues in the heating walls constituted of upper and lower flue sections, groups of reversible regenerators comprising pairs of regenerators operable either conjointly for preheating air or separately for preheating a lean fuel gas and air, connections extending separately to both upper and lower flue sections of the heating walls for conveying alternately in successive 80 periods preheated combustion medium from the regenerators to the flues of the heating walls and waste gases to the regenerators from the flues of the heating walls, waste gas conveying means continuously extending transversely to at least four flued heating walls, duct connections communicably connecting the respective heating walls to said conveying means, and rich gas conduits communicating with both upper and lower flue 85 sections.

18. In a vertical retort battery, a plurality of side-by-side vertical retorts, heating walls intermediate said retorts, vertical flues in the heating walls constituted of upper and lower flue sections, groups of reversible regenerators comprising pairs of regenerators operable either conjointly for preheating air or separately for preheating a lean fuel gas and air, connections extending separately to both upper and lower flue sections of the 90 heating walls for conveying alternately in successive periods preheated combustion medium from the regenerators to the heating walls and waste gases from the flues of the heating walls and the regenerators, waste gas conveying means continuously extending transversely to at least four heating walls, duct connections communicably connecting the respective flued heating walls to said conveying means, and rich gas conduits communicating with both upper and lower flue 95 sections.

nicating with both upper and lower flue sections.

19. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators either conjointly for preheating air or separately for preheating a lean fuel gas and air, connections extending separately to both upper and lower flue sections of the heating walls for conveying alternately in successive periods preheated combustion medium from the regenerators to the flues of the heating walls and waste gases to the regenerators from the flued heating walls, waste gas conveying means continuously extending transversely to at least four heating walls, and duct connections communicably connecting the respective flued heating walls to said conveying means.

20. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators in pairs either conjointly for preheating air or separately for preheating a lean fuel gas and air, connections extending separately to both upper and lower flue sections of the heating walls for conveying alternately in successive periods preheated combustion medium from the regenerators to the flues of the heating walls and waste gases to the regenerators from the flues of the heating walls, waste gas conveying means continuously extending transversely to at least four flued heating walls, duct connections communicably connecting the respective heating walls to said conveying means, and rich gas conduits communicating with both upper and lower flue sections.

21. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators in pairs either conjointly for preheating air or separately for preheating a lean fuel gas and air, connections from the tops of the regenerators extending separately to both upper and lower flue sections of the heating walls for conveying alternately in successive periods preheated combustion medium from the regenerators to the flues of the heating walls and waste gases to the

generators from the flues of the heating walls, waste gas conveying means continuously extending transversely to at least four heating walls, duct connections communicably connecting the bottoms of the respective flued heating walls to said conveying means and rich gas conduits communicating with both upper and lower flue sections.

22. In a vertical retort battery, a plurality of vertical retorts, heating walls flanking said retorts, and disposed therewith in a row along one side of the battery, vertical flues in the heating walls constituted of upper and lower flue sections, reversible regenerators disposed in a row along the opposite side of the battery and with the inflow and outflow regenerators segregated at the opposite sides of the row, means for operating said regenerators in pairs either conjointly for preheating air or separately for preheating a lean fuel gas and air with an air regenerator at the end of the inflow group next the outflow group, connections from the tops of the regenerators extending separately to both upper and lower flue sections of the heating walls for conveying alternately in successive periods preheated combustion medium from the regenerators to the flues of the heating walls and waste gases to the regenerators from the flues of the heating walls, waste gas conveying means continuously extending transversely to at least four heating walls, duct connections communicably connecting the bottoms of the respective flued heating walls to said conveying means and rich gas conduits communicating with both upper and lower flue sections.

23. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery and arranged in side-by-side groups adapted to operate in alternation with each other for inflow and outflow and with the inflow and outflow groups regenerators segregated at opposite sides of the centre of the row, means for operating said regenerators in pairs either conjointly for preheating air or separately for preheating a lean fuel gas and air, a lean gas supply of said means communicating with only interior regenerators of the groups, connections from the tops of the regenerators extending separately to both upper and lower flue sections of the heating walls for conveying alternately in successive periods preheated combustion medium from the regenerators to the flues of the heating walls and waste gases to the regenerators from the flues of the heating walls, waste gas conveying means continuously extending transversely to at least four heating walls, duct connections communicably connecting the bottoms of the respective flued heating walls to said conveying means and rich gas conduits communicating with both upper and lower flue sections.

- bly connecting the bottoms of the respective flued heating walls to said conveying means and rich gas conduits communicating with both upper and lower flue sections.
24. In a vertical retort battery, a plurality of side-by-side vertical retorts, heating walls intermediate said retorts, vertical flues in the heating walls constituted of upper and lower flue sections, reversible regenerators, connections extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery, and duct connections communicably connecting the respective flued heating walls to said waste gas channel. 70
25. In a vertical retort battery, a plurality of side-by-side vertical retorts, heating walls intermediate said retorts, vertical flues in the heating walls constituted of upper and lower flue sections, reversible regenerators, connections extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery, and duct connections communicably connecting the respective flued heating walls to said waste gas channel. 75
26. In a vertical retort battery, a plurality of side-by-side vertical retorts, heating walls intermediate said retorts, vertical flues in the heating walls constituted of upper and lower flue sections, reversible regenerators, connections extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery, and duct connections communicably connecting the respective flued heating walls to said waste gas channel, and rich gas conduits communicating with both upper and lower flue sections. 80
27. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators either conjointly for preheating air or separately for preheating a lean fuel gas and air, connections extending separately to both upper and lower flue sections of the heating walls for conveying alternately in successive periods preheated combustion medium from the regenerators to the flues of the heating wall and waste gases to the regenerators from the flues of the heating walls, a single waste gas channel extending transversely to the heating walls and continuously for substantially the whole length of the battery and duct connections communicably connecting the respective fluid heating walls to said waste gas channel. 85
28. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators either conjointly for preheating air or separately for preheating a lean fuel gas and air, connections extending separately to both upper and lower flue sections of the heating walls for conveying alternately in successive periods preheated combustion medium from the regenerators to the flues of the heating wall and waste gases to the regenerators from the flues of the heating walls, a single waste gas channel extending transversely to the heating walls and continuously for substantially the whole length of the battery and duct connections communicably connecting the respective fluid heating walls to said waste gas channel. 90
29. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators in pairs either conjointly for preheating air or separately for preheating a lean fuel gas and air, connections extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery and duct connections communicably connecting the respective fluid heating walls to said waste gas channel. 95
30. In a vertical retort battery, a plurality of side-by-side vertical retorts, heating walls intermediate said retorts, vertical flues in the heating walls constituted of upper and lower flue sections, reversible regenerators, connections extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery, and duct connections communicably connecting the respective flued heating walls to said waste gas channel, and means for supplying rich gas to the vertical flues. 100
31. In a vertical retort battery, a plurality of side-by-side vertical retorts, heating walls intermediate said retorts, vertical flues in the heating walls constituted of upper and lower flue sections, groups of reversible regenerators comprising pairs of regenerators 105

30. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery, means for operating said regenerators in pairs either conjointly for preheating air or separately for preheating a lean fuel gas and air, connections from the tops of the regenerators extending separately to both upper and lower flue sections of the heating walls for conveying alternately in successive periods preheated combustion medium from the regenerators to the flues of the heating walls and waste gases to the regenerators from the flues of the heating walls a single waste gas channel extending transversely to the heating walls and continuously for substantially the whole length of the battery, duct connections communicably connecting the respective fluid heating walls to said waste gas channel, and rich gas conduits communicating with both upper and lower flue sections.

31. In a vertical retort battery, a plurality of vertical retorts, heating walls flanking said retorts, and disposed therewith in a row along one side of the battery, vertical flues in the heating walls constituted of upper and lower flue sections, reversible regenerators disposed in a row along the opposite side of the battery and with the inflow and outflow regenerators segregated at the opposite side of the row, means for operating said regenerators in pairs either conjointly for preheating air or separately for preheating a lean fuel gas and air with an air regenerator at the end of the inflow group next the outflow group, connections from the tops of the regenerators extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially the whole length of the battery, duct connections communicably connecting the respective fluid heating walls to said waste gas channel, and rich gas conduits communicating with both upper and lower flue sections.

32. In a vertical retort battery, a plurality of vertical retorts, heating walls flanking said retorts and disposed therewith in a row along one side of the battery, vertical flues in the heating walls constituted of upper and lower flue sections, reversible regenerators disposed in a row along the opposite side of the battery and with the inflow and outflow regenerators segregated at opposite sides of the centre of the row, means for op-

erating said regenerators and pairs either conjointly for preheating air or separately for preheating a lean fuel gas and air, a lean gas supply of said operating means serving only interior regenerators of the groups, 70 connections from the tops of the regenerators extending separately to both upper and lower flue sections of the heating walls for conveying alternately in successive periods preheated combustion medium from the regenerators to the flues of the heating walls and waste gases to the regenerators from the flues of the heating walls, a single waste gas channel extending transversely to the heating walls and continuously for substantially 75 the whole length of the battery, duct connections communicably connecting the respective fluid heating walls to said waste gas channel, and rich gas conduits communicating with both upper and lower flue sections. 80

33. In a vertical retort battery, a plurality of blocks or units arranged side by side and each comprising a row of alternate vertical retorts and fluid heating walls therefor arranged side by side and extending alongside a row of reversible regenerators communicably connected with the flues of the heating walls, said blocks having their respective heating walls operatively disposed in two series operable in alternation with each other 95 for inflow and outflow, the inflow heating walls and inflow regenerators being segregated at one end of each block and the outflow heating walls and outflow regenerators segregated at the other end of each block, 100 and a channel continuously extending across the ends of the heating walls in the block and communicably connected to the flues of the heating walls of the block.

34. A vertical retort battery consisting of 105 a plurality of blocks or units as specified in claim 33 arranged side by side with the similarly functioning halves of neighboring blocks next each other.

35. In a vertical retort battery, a plurality of blocks or units arranged side by side and each comprising a row of alternate vertical retorts and fluid heating walls therefor arranged side by side and extending alongside 110 a row of reversible regenerators communicably connected with the flues of the heating walls, said blocks having their respective heating walls operatively disposed in two series operable in alternation with each other for inflow and outflow, the inflow heating 115 walls and inflow regenerators being segregated at one end and the outflow heating walls and outflow regenerators at the other end of each block, means for operating the regenerators in pairs either conjointly for preheating air or separately for preheating air and a lean gas said means being organized so that a regenerator for air is always present at the junction place between inflow 120 and outflow regenerators of each block, and 125 130

a channel continuously extending across the ends of the heating walls in the block and communicably connected to the flues of the heating walls of the block.

36. A vertical retort battery consisting of a plurality of blocks or units as specified in claim 35 arranged side by side with the similarly functioning halves of neighboring blocks next each other.

37. In a vertical retort battery, a plurality of high vertical retorts, heating walls flanking said retorts and disposed therewith in a row extending along one side of the battery, vertical flues in said heating walls having intercommunicating upper and lower flue sections, burners at the upper ends of both sections of each flue, a waste heat channel extending continuously transversely to the heating walls and communicably connected separately to the bottom of each flued wall, reversible regenerators extending in a row along the opposite side of the battery, direct duct connections from the tops only of the regenerators to both upper and lower burners, sole channels at the bottoms only of the regenerators for admitting the medium to be preheated and discharging the waste gases, means for operating said regenerators in pairs either conjointly for preheating air or separately for preheating air and a lean gas and with a regenerator for air always at the end of the inflow group of regenerators that is next the outflow group of regenerators, and a rich gas supply duct 35 to each burner.

In testimony whereof, I have hereunto set my hand.

JOSEPH VAN ACKEREN.
